DESIGN FOR A HANDBAG

Florence N. Lewis, New York, N. Y.

Application October 15, 1941, Serial No. 103,770

Term of patent 7 years

To all whom it may concern:

Be it known that I, Florence N. Lewis, a citizen of the United States of America, residing in New York city, county of New York, and State of New York, have invented a new, original, and ornamental Design for a Handbag, of which the following is a specification, reference being had to the accompanying drawing, forming part thereof, wherein,

Figure 3 is a rear elevational view of the handbag drawn on a smaller scale, and a portion of the handle being omitted for convenience of illustration.

I claim:

The ornamental design for a handbag, substantially as shown, and described.

FLORENCE N. LEWIS.
